US00D956856S

(12) **United States Design Patent** (10) **Patent No.:** **US D956,856 S**
(45) **Date of Patent:** **** Jul. 5, 2022**

(54) **EXTENSION SUPPORT**

(71) Applicant: **AUTEL INTELLIGENT TECHNOLOGY CORP., LTD.**,
Guangdong (CN)

(72) Inventor: **Yongshuai Wang**, Guangdong (CN)

(73) Assignee: **AUTEL INTELLIGENT TECHNOLOGY CORP., LTD.**,
Shenzhen (CN)

(**) Term: **15 Years**

(21) Appl. No.: **29/732,906**

(22) Filed: **Apr. 28, 2020**

(30) **Foreign Application Priority Data**

Oct. 30, 2019 (CN) 201930593679.3

(51) **LOC (13) Cl.** **16-04**

(52) **U.S. Cl.**

USPC **D16/250**

(58) **Field of Classification Search**

USPC D16/136, 211, 214, 219, 235, 236, 237,
D16/241, 242, 243, 245, 250, 334;
D8/352, 353, 354, 381, 382, 394
CPC .. G03B 17/561; G03B 17/563; G03B 17/566;

(57) **CLAIM**

The ornamental design for an extension support, as shown and described.

DESCRIPTION

FIG. 1 is a front elevational view of an extension support showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

1 Claim, 4 Drawing Sheets
